UNITED STATES PATENT OFFICE.

FRANK MORGAN, OF MELROSE, MASSACHUSETTS.

STARTING DEVICE FOR INTERNAL-COMBUSTION ENGINES.

1,142,193.

Specification of Letters Patent.

Patented June 8, 1915.

Application filed October 4, 1913. Serial No. 793,479.

To all whom it may concern:

Be it known that I, FRANK MORGAN, a subject of the Kingdom of Great Britain, residing at Melrose, in the county of Middlesex and State of Massachusetts, have invented a new and useful Improvement in Starting Devices for Internal-Combustion Engines, of which the following is a specification, reference being had therein to the accompanying drawings.

This invention relates to a starting device for internal combustion engines in which fluid under compression is utilized as the motive power.

The main object of my invention is to provide a starting device of the above character which is simple, efficient and of low cost both in construction and operation.

Another object of the invention is to provide a device which is entirely self-contained and in which the fluid used for starting the engine is compressed by a pump or other device operated by the engine.

A further object of the invention is to save wear on the pump or other device used for compressing the operating fluid, and to this end means are provided whereby the compressing device is automatically thrown into and out of operation as required to maintain a constant pressure of fluid.

An additional object of the invention is to secure an accurate distribution of the compressed fluid to the proper cylinders in the starting operation and to this end means are provided for operating the distributing device from the main shaft of the engine independently of the operation of the compressing device.

Other objects of the invention will be more specifically set forth and described hereinafter.

The preferred embodiment of my invention comprises, briefly, a suitable pump or other device adapted to be operated by the engine, a storage reservoir for holding the fluid which is compressed by the pump, means for distributing the fluid under compression to the cylinders of the engine to start the same and means for automatically throwing the pump or other compressing device into and out of operation as required to maintain a constant pressure in the storage tank.

In the accompanying drawings illustrating the preferred embodiment of my invention, Figure 1 is a diagrammatic view of an

apparatus constructed and operated in accordance with my invention; Fig. 2 is a vertical, central, longitudinal sectional view of the compression device and distributing means; Fig. 3 is a cross sectional view of the same, partly in elevation, on line 3—3 looking from right to left in Fig. 2; Fig. 4 is an elevation of the distributing device with the distributing disk removed, looking from right to left in Fig. 3; Fig. 5 is a side elevation of the distributing disk.

Referring to Fig. 1 of the drawings illustrating one embodiment of the invention applied to a four cylinder internal combustion engine, 7, 8, 9 and 10 designate the four cylinders, 11 a main shaft, 12 a crank case and 13 a fly wheel mounted on the main shaft, all of old and well known construction. The position of the pistons in the various cylinders is shown in dotted lines. To hold a supply of the compressed operating fluid, preferably air, a suitable reservoir 14 is provided and connected to a compressing device 16 by a pipe 17 and to a distributing device by a pipe 18 controlled by a valve 19 which may be operated from a distance by a rod 20 or in any suitable manner. From the distributing device the compressed fluid is delivered to the cylinders 7, 8, 9 and 10 by pipes 21, 22, 23 and 24 respectively. With this arrangement the compressing device forces the compressed fluid into the reservoir through the pipe 17, whence it flows through the pipe 18 when the valve 19 is open to the distributing device where it is delivered to the four cylinders through the pipes 21, 22, 23 and 24 in the proper sequence.

Although any suitable form of compression means may be employed, I prefer to use a pump of the form shown on an enlarged scale in Fig. 2, comprising a pump cylinder 26 mounted on a crank casing 27 and a piston 28. The latter is operated by an eccentric 29 within a strap 30 having an integral arm 31 pivotally connected to a cross-pin 32 in the piston. The eccentric is held within the strap by a projecting flange 33 on one side and a cross-piece 34 fastened to the other side of the eccentric by screws 35. The compression end of the pump cylinder may be provided with an inlet valve 36 to admit air to the cylinder when the piston is on the suction stroke and with an outlet valve 37 to permit air under pressure to flow into the reservoir through the pipe 17 when the pres-

sure in the cylinder of the pump exceeds the pressure in the reservoir. Any well known and suitable form of valve may be employed for these purposes such as that 5 shown in the drawings which consists of a ball 38 held in a seated position to close the valve by a spring 39. The pump cylinder may be provided with fins 40 for cooling purposes. The means for operating the 10 pump will be described hereafter as they are intimately associated with the means for operating the distributing device.

In the form of distributing means shown, I provide a circular disk 41 mounted within 15 a distributing chamber 42 which is formed in one end of the crank casing 27 and closed by a plate 43 bolted to the casing by bolts 44. The disk has an outwardly extending hollow hub 45 which in interior cross-section 20 is square to receive the squared end 46 of a shaft 47 in order that the disk may rotate with the shaft. The distributing pipes 21, 22, 23 and 24 are connected to suitable passages 48 in the crank casing which lead to 25 the distributing chamber 42 and enter it at four different points as shown in Fig. 4 where the disk is shown as removed. The disk is provided with an elliptical port 49 which registers with the four different passages 48 in rotation and admits fluid under 30 pressure from the distributing chamber to the cylinders in turn. The end plate 43 has also a central outwardly extending hub 50 to conform to the shape of the disk and to 35 accommodate a spring 51 which bears at one end against the hub 50 and at the other end against the disk hub to force the disk into air tight engagement with the casing 27 and to prevent leakage of air from the distributing 40 chamber into the passages 48. A pin 52 keeps the spring in central position on the hub of the disk. This spring may, however, in some cases be dispensed with as the pressure of the air which flows into the distributing 45 chamber through the pipe 18 from the reservoir will generally be sufficient to maintain a tight joint. The spring by exerting a continuous pressure prevents the disk becoming unseated when the valve 19 is closed 50 and the air pressure reduced and thereby prevents the entrance of dirt between the disk and its seat which otherwise might prevent a perfect seat and cause a leak.

The compressing means and the distributing 55 means are both operated by the engine but independently of each other so that the pump may be thrown out of operation when the pressure in the reservoir reaches a certain maximum, without interfering with the continuous operation of the distributing means. It is necessary that the latter means be operated continuously in order that the distribution of the compressed fluid may be properly timed to flow into the proper cylinders of the engine. Any means may be

used for this purpose and one such is shown in the drawings. The shaft 47 which carries the distributing disk 41 extends through the crank casing 27 and has mounted upon its outer end a gear-wheel 54 meshing with 70 a gear-wheel 55 mounted on the main shaft 11 of the engine. The two gear-wheels are so proportioned that the gear-wheel 54 makes one revolution for each two revolutions of the engine shaft in a four cylinder engine. The result is that the distributing disk 41 is rotated whenever the engine is operated. Upon the shaft 47 is mounted a sleeve 56 to which the eccentric 29 which operates the pump is secured; the eccentric being provided with a hub 57 extending outwardly on both sides and engaging at each end the crank casing 27. The sleeve 56 is rotated by the shaft 47 by means of a clutch 80 of any suitable form. As shown the clutch comprises a female member 58 secured to one end of the sleeve and a male member 59 secured to the shaft by a key 60. The clutch is thrown into and out of operation by moving the shaft 47, clutch member 59 90 and gear-wheel 54 as a unit.

In Fig. 2 the mechanism is shown with the clutch in operative position. When it is thrown out of operative position the parts are moved to the left and for this reason the 95 gear-wheel 54 is made wider in order to engage the gear-wheel 55 when in either position. To operate the clutch, a clutch lever 62 pivotally fastened at its lower end to a bracket 64 on the casing 27 may be provided, 100 the lever having a yoke 65 with pins 66 engaging an annular groove in the male member 59 of the clutch. This lever may be operated by hand or automatically as preferred. I have shown it as operated automatically by the pressure in the storage reservoir so that when the pressure in the reservoir reaches a certain pre-determined maximum the pressure operates to disconnect the clutch and stop the pump or pressure creating device and when the pressure falls below a certain pre-determined amount the clutch is thrown into operation to start the pump. To accomplish this result the pump cylinder may be provided with an extension 68 on 115 one side to form a chamber 69 in which is arranged a diaphragm 70 of leather or other suitable material. A passage 71 connects the inner part of the chamber 69 with the chamber of the valve 37 and the diaphragm 120 is at all times subjected to the pressure of the storage reservoir. To the center of the diaphragm is secured by a nut 72 and washers 73 a rod 74 which passes through the outer end of the extension 68 and is pivotally connected to the upper end of the clutch lever 62. A helical spring 75 is arranged upon the rod 74 between the extension 68 and the diaphragm to prevent operation of 125 the clutch until the maximum pressure has 130

been reached in the storage reservoir. To prevent operation of the clutch for slight variations in the storage pressure the side of the extension is bored and a ball 77 is placed therein in position to engage notches 78 in the rod 74, the ball being held in position by a spring 79 and a screw 80. By turning the latter the pressure exerted by the spring may be regulated and the operation 10 of the clutch correspondingly affected.

The operation of my device is as follows: The dotted outlines in Fig. 1 show the normal position of the pistons when the engine is at rest with the valve 19 closed. 15 To start the engine the valve 19 is opened which permits the compressed fluid to flow from the reservoir through the pipe 18 into the chamber 42 and port 49 into one of the pipes to the proper cylinder. The pipes 21, 20 22, 23 and 24 may be controlled, if desired, by valves 82 and when so controlled all of these valves should be opened before operating the valve 19. Owing to the fact that the distributing disk 41 is operated directly 25 from the main shaft of the engine the port 49 always registers with the proper opening 48 so that the compressed fluid when first admitted to the distributing chamber will flow into that cylinder in which the piston 30 is on the firing stroke when the engine is running. The admission of the compressed fluid moves the piston of the engine which action rotates the main shaft and turns the distributing disk to the next opening 48 35 thereby admitting the compressed fluid to another cylinder. The result is that the engine is operated by the compressed fluid acting on the pistons in the different cylinders in proper rotation until the explosive mixture has been drawn into the cylinders 40 and fired by the ignition means, which starts the engine. To provide for a slight variation in the location of the pistons when the engine stops, the port 49 is elongated so that 45 it registers with one of the openings 48 even if the piston for that opening is not at the extreme end of its compression stroke. After the engine is started the operator, by manipulation of the rod 20 closes the valve 50 19 and thereby checks the flow of compressed fluid to the cylinders. Whenever, as for instance, after a starting operation, the pressure in the starting reservoir 14 falls below the maximum and to a degree sufficient to 55 reduce the pressure on the diaphragm 70 so that the spring 75 returns it to a normal position as shown in Fig. 2 of the drawings the male clutch 59 is thrown into engagement with the female clutch member 58 60 thereby causing a rotation of the sleeve 56 to operate the pump. For instance, if the maximum pressure in the storage reservoir is 175 pounds, then the locking device comprising the ball 77 and spring 79 should be 65 so adjusted as to lock the rod 74 against

movement until the pressure has dropped some 25 pounds to 150 pounds. At this point, by making the proper adjustments of the locking device the spring 75 will overcome the resistance of the locking device 70 and throw the rod 74 inwardly, thereby operating the clutch to start the pump as above described. As soon as the pressure is increased in the storage reservoir to the maximum, the pressure upon the diaphragm 75 70 overcomes the resistance of the spring 75 and the locking device and throws the rod 74 outwardly disconnecting the clutch and the pump stops. In consequence the pressure in the storage reservoir never exceeds 80 175 pounds and never falls below 150 pounds.

It will be noted that the automatic feature of this device is an important one because it eliminates the necessity of watching the 85 pressure in the storage reservoir and at the same time reduces the wear on the pump to a minimum. Another important feature of my invention is that the pump and distributing devices are operated independently of 90 each other. This is absolutely necessary because the distributing device must be so timed that the compressed fluid will be admitted to the proper cylinder in starting the engine and unless the distributing device is 95 directly connected to and operated from the main shaft of the engine this result is impossible.

It is to be observed that my device is of extreme simplicity, that it is entirely self-contained, that it requires no electrical or other extraneous power to operate it, and that it is so constructed that it cannot get out of order or become inoperative.

Although I have shown and described my 100 invention as applied to an internal combustion engine having four cylinders, I do not wish to limit it to that particular kind or type of engine, since it may be applied to any internal combustion engine having more 105 or less cylinders than four.

It is to be understood that my invention is not to be limited to the exact construction herein shown and described as it may be embodied in other forms of construction and 110 I desire to claim it broadly within the scope 115 of the following claims.

What I claim is:-

1. A starting device for internal combustion engines comprising in combination 120 with an internal combustion engine a shaft, means on one end of said shaft for driving it from said engine, a rotary distributor operated by said shaft; a sleeve loosely mounted on said shaft, a pump operated by 125 said sleeve and means for operatively connecting said sleeve to said shaft to operate said pump.

2. A starting device for internal combustion engines comprising in combination 130

with an internal combustion engine a shaft, means on one end of said shaft for driving it from said engine, a rotary distributor operated by said shaft, a sleeve loosely mounted on said shaft, a pump operated by said sleeve and automatic means for operatively connecting said sleeve to said shaft to operate said pump when the pressure of the working fluid falls below a predetermined point.

3. A starting device for internal combustion engines comprising in combination with an internal combustion engine a shaft, means on one end of said shaft for driving it from said engine, a rotary distributor operated by said shaft, a sleeve loosely mounted on said shaft, a pump operated by said sleeve and a clutch for operatively connecting said sleeve to said shaft to operate said pump when the pressure of the working fluid falls below a predetermined point.

4. A starting device for internal combustion engines comprising in combination with an internal combustion engine a shaft,
25 means on one end of said shaft for driving it from said engine, a rotary distributor operated by said shaft, a sleeve loosely mounted on said shaft, a pump operated by said sleeve, a clutch, and automatic means for operating said clutch when the pressure of the working fluid falls below a predetermined point.

5. A starting device for internal combustion engines comprising in combination
35 with an internal combustion engine a shaft, means on one end of said shaft for driving
it from said engine, a rotary distributor operated by said shaft, a sleeve loosely mounted
40 on said shaft between said driving means and said distributor, a pump operated by
said sleeve and means for operatively connecting said sleeve to said shaft to operate
said pump.

6. A starting device for internal combus-

tion engines comprising in combination 41 with an internal combustion engine a shaft, means on one end of said shaft for driving it from said engine, a rotary distributor operated by said shaft, a sleeve loosely mounted on said shaft between said driving means 50 and said distributor, a pump operated by said sleeve and automatic means for operatively connecting said sleeve to said shaft to operate said pump when the pressure of the working fluid falls below a predetermined 55 point.

7. A starting device for internal combustion engines comprising in combination with an internal combustion engine a shaft, means on one end of said shaft for driving it from said engine, a rotary distributor operated by said shaft, a sleeve loosely mounted on said shaft between said driving means and said distributor, a pump operated by said sleeve and a clutch for operatively connecting said sleeve to said shaft to operate said pump when the pressure of the working fluid falls below a predetermined point.

8. A starting device for internal combustion engines comprising in combination 70 with an internal combustion engine a shaft, means on one end of said shaft for driving it from said engine, a rotary distributor operated by said shaft, a sleeve loosely mounted on said shaft between said driving means 75 and said distributor, a pump operated by said sleeve, a clutch, and automatic means for operating said clutch when the pressure of the working fluid falls below a predetermined point. 80

In testimony whereof, I hereunto set my hand in the presence of two subscribing witnesses, this the second day of October, 1913.

FRANK MORGAN.
